UNITED STATES PATENT OFFICE

JAMES W. BARNETT, OF SPOKANE, WASHINGTON

DESIGN FOR A DOORSTOP

Application filed September 16, 1930. Serial No. 36,986. Term of patent 3½ years.

To all whom it may concern:

Be it known that I, JAMES W. BARNETT, a citizen of the United States of America, residing at Spokane, in the county of Spokane and State of Washington, have invented a new, original, and ornamental Design for a Doorstop, of which the following is a specification, reference being had to the accompanying drawing, forming a part thereof.

Figures 1 and 2 represent respectively a front and side elevation of the door stop showing my new design.

I claim:

The ornamental design for a door stop as shown.

JAMES W. BARNETT.
